CLAIM

The ornamental design for combined battery charger, power supply and battery tester, substantially as shown and described.

DESCRIPTION

FIG. 1 is a front perspective view of the combined battery charger, power supply and battery tester from above showing my new design;

FIG. 2 is a rear perspective view thereof from below; FIG. 3 is a top plan view thereof with the lid removed; FIG. 4 is a cross-sectional view thereof taken on the line 4—4 in FIG. 3, and

FIG. 5 is a cross-sectional view thereof taken on the line 5—5 of FIG. 3.

FIG. 1

FIG. 2

FIG. 3

FIG. 4

FIG. 5
